(57) **CLAIM**

The ornamental design for a charger for an electric skin brush applicator, as shown and described.

DESCRIPTION

FIG. 1 is an isometric view of the charger for an electric skin brush applicator showing the new design;

FIG. 2 is a top view of the charger;

FIG. 3 is a bottom view of the charger;

FIG. 4 is a side elevational view of the charger, the other side being a mirror image thereof;

FIG. 5 is an elevational view of one end of the charger; and, FIG. 6 is an elevational view of an opposing end of the charger.

The broken lines showing portions of the charger are included for the purpose of illustrating environmental structure and form no part of the claimed design.
